UNITED STATES PATENT OFFICE.

IRV E. SMITH, OF STOCKTON, CALIFORNIA.

AUTOMATIC CUT-OFF DEVICE FOR OIL-BURNER MOTORS.

Original application filed November 17, 1924, Serial No. 750,248. Divided and this application filed June 30, 1926. Serial No. 119,626.

This invention relates to improvements in electrically driven oil burning apparatus, and particularly represents a divisional application of my co-pending application for 5 patent on oil burning apparatus, filed November 17th, 1924, Serial No. 750,248.

The present application relates to the automatic cut-off device for the oil burner motor, my principal object being to provide a 10 simple and positively acting device to cause the motor to be stopped in the event that an excessive supply of oil, which is not all being burnt, is being fed to the burner plate, or the float controlled supply device itself 15 floods and overflows.

This stopping of the motor, without the presence of an operator being necessary, prevents possible damage from fire which might occur around the burner if the defective flow of oil were allowed to continue 20 unnoticed, and also notifies the operator when such conditions obtain so that he may make the necessary investigation and adjustments before again attempting to start 25 the motor.

These objects I accomplish by means of such structure and relative arrangement of parts as will fully appear by a perusal of the following specification and claims.

30 In the drawings similar characters of reference indicate corresponding parts in the several views:

Fig. 1 is a side elevation of the complete unitary assembly of the apparatus.

35 Fig. 2 is a detached and enlarged view of an automatic motor circuit controlling member whose action is controlled by an overflow of oil either from the burner or from the float control supply member.

40 Fig. 3 is a sectional view of the burner detached.

Referring now more particularly to the characters of reference on the drawings, the burner in general comprises a vertical and 45 tubular casing in which is turnably and closely fitted a shaft 2. On the lower end of this shaft is a centrifugal pump runner 3 adapted to take oil from a passage 4 formed in a bottom cap 5 and to discharge 50 such oil through suitable passage means 6 leading to the top of the shaft.

On top of the shaft is mounted a burner plate 7 of suitable character onto which the oil from the passage 6 is thrown with the 55 rotation of the shaft 2 and the operation of

the pump. Mounted on the shaft 2 below the plate is a gear 8 driven from a shaft 9 connected to an electric motor 10. The motor and casing 1 are rigidly mounted in unitary relation on a common base 11. 60

The burner plate is surrounded by a casing 12 having an opening 13 at the bottom thereof under which opening and fixed on the member 1 is a dish 14. This dish has a downward slope towards its center and is 65 adapted to catch any excess oil dropping from the burner plate and casing 12 and for some reason not consumed with the operation of the burner. A drain pipe 15 leads from this dish to a device hereinafter 70 explained.

Also mounted on the base 11 adjacent the outer end thereof is an oil supply control device, comprising a bowl 16 having a float 17 thereon which automatically controls the seating of a needle valve 18 in the oil intake passage 19, so that the oil in the body may be maintained at a definite level as at A, and at the same time the oil pump 3 will be supplied with the necessary amount 75 of fuel. This form of construction being common to various carburetors and the like, as will be evident, no further explanation of the working thereof is thought necessary. The oil is preferably fed to the intake 19 in a suitable manner, preferably by means of a pump 20 driven by the motor 10. 80

An outlet pipe 21 leads from the bowl 16 near the bottom thereof to the passage 90 4 of the casing 1, so as to supply the pump 3 with a gravity flow of oil.

A pipe 22 leads downwardly from the bowl 16 above the normal oil level line A thereof, so as to take oil away from the 95 bowl in the event that the float or valve stick or fail to function properly and causing the oil to rise to an undue height in the bowl.

Automatic shut-down of the motor, 100 should the above conditions in the bowl obtain, or if oil should be excessively discharged into the dish 36 of the burner, is provided for by the following structure:

Both pipes 15 and 22 empty into a small 105 open topped tank 23 positioned adjacent the base at any suitable point outside the furnace and having a bail 24 removably hung on one end of a horizontal lever 25. This lever is fulcrumed on a bracket 26 which 110

is mounted on the base 11. A weight 27 on the lever counteracts the weight of the tank 23 when the latter is empty, this counteracting weight, after a small amount of oil 5 has flowed into the tank, being aided by the weight of a float 28 in the tank and held clear of the bottom thereof, as will be hereinafter seen. The bracket 26 is of such a height that the tank is freely suspended 10 clear of the base.

Vertically opposed contacts 29 are arranged in connection with the weight 27, these contacts being normally spaced from but adapted to alternately engage contacts 15 30 fixed on the bracket 26. In the main circuit leads 31 to the motor 10 is interposed a normally closed switch 32 preferably of the thermostat type. The heating element 33 of this switch is connected by a lead 34 20 to the corresponding lead 31 ahead of the switch, and has a connection with the contacts 29 through the bracket 26 and lever 25. The contacts 30 are connected in common to the other lead to the motor by means 25 of a lead 35.

The stem 36 of the float 28 has a yoke 37 straddling the lever 25 on the opposite side of the fulcrum thereof from the bail 24. This yoke has a cross pin 38 below the lever 30 adapted to engage the same only after the float has risen a certain distance. A similar pin 39 is mounted in the yoke above the lever and is normally just clear of the same. The float is normally supported clear of the 35 tank and the pin 39 clear of the lever by means of adjustable nuts 40 on the float stem, which nuts rest on an extension 26^a of the bracket, said extension also forming a guide for the stem. The nuts are preferably 40 adjusted so that the pin 39 is just barely clear of the lever when the tank is empty. Therefore, while the weight 27 alone counterbalances the weight of the empty tank, as soon as any oil flows into the latter and 45 the lever adjacent the pin 39 starts to rise, said pin will take hold and the weight of the float will then aid in counteracting the weight of the tank. In this manner, a relatively large amount of oil may flow into 50 the tank before the upper contacts 29 and 30 engage each other, as will be evident. After a certain amount of oil has entered the tank, however, either through the pipe 15 or through the pipe 22, the counterbalancing effect of the weight 27 and that of the float will be overcome. This will cause 55 the tank to lower and the thermostat switch heater circuit to be closed at the upper contacts 29 and 30. The heater element 33 of said switch will therefore be heated, causing the switch 32 to be opened and the motor circuit consequently broken. When the tank 60 is disconnected from the lever 25 for emptying, the removal of its weight from the lever 65 causes the weight 27 to be lowered so that

the lower contacts 29 and 30 become engaged. This of course causes the stoppage of the motor in the same manner as above, so that the latter cannot be run or the burner operated until the tank is replaced in 70 position on the lever in an empty condition.

Should any person attempt to frustrate the functioning of the device by blocking up the tank 23 so that it will not lower when oil drains therein, the rising float with the 75 accumulation of oil in the tank will cause the lever to tilt and the upper contacts 29 and 30 to be engaged just the same as if the tank itself were lowered and caused this movement of the lever to take place. This 80 is because after the float has risen a certain distance the pin 38 bears against the lever 25 causing the latter to move without any movement of the tank itself. When the lever thus moves, while the tank is stationary, the end of said lever adjacent the tank drops away from the bail 24, but since this bail is not permanently affixed to the lever no strain is placed on the lever or bail. 85

I am aware that overflow tanks, operating 90 knife-switches, have been used for a similar purpose. As far as I am aware however, they only operate in one direction, that is when the tank is lowered with a weight of oil therein. As soon as these 95 tanks are removed, the circuit is restored to an unbroken condition.

This is contrary to my arrangement, with which breaking of the motor circuit is had when the tank is full, when it is removed, 100 and if the tank should be blocked up and prevented from downward movement. This construction meets the requirements of the Fire Underwriters, in providing a device which automatically operates under any and 105 all conditions.

Further, the particular form of motor-circuit control switch enables the switch control circuit to be of low voltage, which allows abutting and sensitive contacts to be 110 used instead of the knife switch which requires more power.

From the foregoing description it will be readily seen that I have produced such a device as substantially fulfills the objects 115 of the invention as set forth herein.

While this specification sets forth in detail the present and preferred construction of the device, still in practice, such deviations from such detail may be resorted to as 120 do not form a departure from the spirit of the invention, as defined by the appended claims.

Having thus described my invention what I claim as new and useful and desire to secure by Letters Patent is:

1. In an oil burner having a burner member onto which oil is fed, an electric motor by means of which oil is fed to the member, means for catching any excess oil from the 130

member, a normally counterbalanced and suspended tank into which such excess oil is automatically discharged, said tank being removable, and means whereby when the tank is either removed, or overbalanced by the weight of a certain amount of oil therein, the motor will be automatically stopped.

2. In an oil burner having a burner member onto which oil is fed, an electric motor by means of which oil is fed to the member, means for catching any excess oil from the member, a tank into which said oil is automatically discharged, a horizontal lever on which the tank is removably hung, means on the lever normally holding the tank counterbalanced, a normally closed switch in the motor circuit, an independent and normally open circuit for opening the switch, and means whereby movement of the lever in either direction about its fulcrum will cause the switch-opening circuit to be closed.

3. In an oil burner having a burner member into which oil is fed, an electric motor by means of which oil is fed to the member, a normally closed switch in the motor circuit, a lever, a normally counterbalanced tank suspended from the lever into which any excess oil from the plate is automatically fed, means whereby a movement of the lever

caused by the downward movement of the tank when oil enters the same, will cause the switch to be opened, float means in the tank, and means between the lever and float whereby if the tank is prevented from downward movement the float will cause movement of the lever to open the switch when oil flows into the tank.

4. In an oil burner having a burner member onto which oil is fed, an electric motor by means of which oil is fed to the member, a normally closed switch in the motor circuit, a lever pivoted intermediate its ends, a tank suspended from one end of the lever, a weight on the other end of the lever normally counterbalancing the weight of the empty tank, a float in the tank, means whereby after a certain amount of oil has passed into the tank the weight of the float will be added to that of the lever weight to aid in counterbalancing the weight of the tank and oil therein, and means whereby when the lever moves with the overbalancing thereof by reason of a certain amount of oil in the tank, the switch will be opened.

In testimony whereof I affix my signature.

IRA E. SMITH.
